FIG. 4

UNITED STATES PATENT OFFICE

CARL GEORG BERTIL ROTHÉLIUS, OF STOCKHOLM, SWEDEN, ASSIGNOR TO AKTIE-BOLAGET FORMATOR, OF STOCKHOLM, SWEDEN

MACHINE FOR STRIPPING TOBACCO LEAVES

Application filed January 7, 1929, Serial No. 330,715, and in Sweden December 8, 1928.

The present invention relates to machines for stripping tobacco leaves of the type provided with a gripper or the like by means of which the stem of the leaves is gripped preferably at some distance from the point of the leaf whereupon the gripper and the leaf are given a suitable movement in relation to each other.

In consequence of the resistance arising for different causes against the tearing out of the stem the latter may break especially at or in the vicinity of the place where it is gripped and where it is usually rather weak.

It may also happen that the gripper lets go the stem when during the stripping the resistance against the tearing out of the stem becomes too powerful; for instance owing to the stem branches becoming thicker as they are located nearer the base of the leaf. The stem thus attached to the leaf then enters with the same into the machine, for instance a bookbinding machine so that a time-wasting elimination of these stems must be effected by hand.

Stripping machines of the present type should preferably be provided with a so-called cleaning device, i. e. a device for cleaning the stem as it is torn out of the leaf from leaf portions sticking thereto. The resistance against the tearing out of the stem will then be increased as the cleaning member or members operate on the stem in a direction opposite to that in which the stem moves on being torn from the leaf.

The device according to the present invention which has for its object to remove the said inconveniences is especially contemplated to be adapted to stripping machines of the kind described which are provided with a cleaning device such as previously set forth. Of course the invention may as well be applied to stripping machines without such cleaning device.

The invention is substantially characterized in that a roller device for feeding the stem is arranged at the path of movement of the gripper in such a way that it is kept inoperative when the gripper passes by the same, but thereafter assumes such a position

tinued tearing out of the stem from the leaf together with or instead of the gripper.

The invention is illustrated in the accompanying drawings where Fig. 1 shows a device according to the invention viewed from one side with the parts in starting position. Figs. 2 shows the arrangement viewed from the front in the direction of the arrow *a* in Fig. 1. Fig. 3 shows viewed from the side and partially in section the positions of the cleaning device and the stem feeding roller device just as the gripper passes these devices. Fig. 4 shows the position of said devices in the moment when the gripper has passed them. Fig. 5 is a section on the line V—V in Fig. 4. Fig. 6 is a section on the line VI—VI in Fig. 4.

The tobacco leaf 30 is threaded onto the gripper 1 when the latter assumes its upper position (Fig. 1), the gripper gripping the leaf stem 31 more or less near the point of the leaf which point extends inwards over the lower 3 of the two band paths 2 and 3 which are movable towards and from one another and which in their shut up position (see Figs. 3 and 4) form a device for feeding the leaf into the machine, for instance a bookbinding machine as in the example shown.

4 designates the carrier of the gripper, said carrier having the form of an arm which may be swung up and down about the shaft 5 and which transfers the gripper from said upper position to a lower position, and then takes it back to the starting position, etc.

According to the embodiment shown by way of example the leaf and the stem are given such a movement in relation to one another that the stripping takes place on the front side of the fore roller 32 of the feeding path 3 (as shown in Figs. 3 and 4).

The said roller device for feeding and tearing out the stem after the latter has been partially torn out by the gripper consists in the embodiment shown of two rollers or cylinders 6 and 7 of which the one 6 is secured to a shaft 9 journaled in the frame 8 and is rotated in the sense of the arrow 10 (Fig. 1) from the driving shaft 11 of the machine by means of the sprocket 12 fixed on the shaft 9, the sprocket 13 fixed on the driving shaft and

the driving chain 14. The other roller 7 is rotatably journalled on a pin 15 which is fixed at the upper forked part 17 of the arm 16. The arm 16 is rigidly secured to a shaft 18 rotatably journalled in the frame 8 and receives a movement towards and from the roller 6 by a suitable device. In the drawing this movement-transferring device consists partly of a cam disk 19 arranged on the driven shaft 20 with which disk cooperates a roller 21 arranged on a fork 22 embracing a guide member 25 on the shaft 20, which fork is connected with an arm 24 by means of the pulling rod 23, said arm 24 being rigidly secured to the shaft 18, and partly of the spring 26 interposed between the frame 8 and the arm 24.

The peripheral surfaces of the rollers 6 and 7 are usually smooth but in certain cases furrowed preferably as shown in the drawing, i. e. their periphery is undulated in cross section.

The two members 33 and 34 of the cleaning device cooperating with the stem are situated rather immediately above the rollers 6 and 7, viz. between said rollers and the fore guide roller 32 of the lower band path 3. One of the members 34 is stationary and provided in the surface facing the stem with a small recess for said stem, whereas the other member 33 consists of a toothed wheel or a cutter, secured to a shaft 35, which is rotatably journalled on the upper forked end of an arm 36, the lower end of which is rotatably journalled on the shaft 18. The cutter shaft 35 is rotated in the sense of the arrow 37 from the driving shaft 11 by means of the rope pulley 38 secured to the last-mentioned shaft, the rope 39, the rope pulley 40 arranged on the tube 41 which encloses the shaft 18, the rope pulley 42 also arranged on the said tube, the rope 43 and the rope pulley 44 on the shaft 35 of the cutter 33.

The member 34 is secured, by means of a screw, to a cross rod 54, fastened between the long shanks of two forks 51 which are arranged on the shaft of the guide roller 32 of the belt path 3 and are kept clamped to this shaft by means of a clamp screw 52.

The arm 36, carrying the cutter wheel 33 is kept engaged against an abutment 46 on the arm 16 by means of an abutment 45 on said arm 36 under the influence of the pulling spring 47 interposed between the arms.

In order to prevent the stem from coiling itself up on the rollers and also to keep the roller surfaces clean a scraper 27 is provided at one of the rollers or, as shown in the drawing, at both of them. One of these is adjustably secured to a member 28 rigidly secured to the cross bar 54 whereas the other one is adjustably fixed at the forked end 17 of the arm 16.

When the gripper 1 assumes its upper position, the roller 7 and the cutter wheel 33 are in their outer (left, Fig. 1) extreme position

in order to afford a free passage for the gripper between said roller 7 and the cutter wheel 33 on the one hand and the roller 6 and cleaning member 34 on the other hand.

When the gripper lowers itself the arm 16 and therewith the roller 7 by the influence of the spring 26 begin their movement in direction towards the roller 6, the arm 36 being caused to follow until its lower end 48 engages the abutment 49 on the cross bar 50 belonging to the frame. The arm 36 with the cutter wheel 33 has then reached its inner extreme position, and the cleaning begins. The gripper has then just passed between the cleaning members 33 and 34 and is passing between the rollers 6 and 7.

The arm 16 with the roller 7 continues, however, its inward movement towards the shaft 6 under the influence of the spring 26 until the roller 7 arrives in operative position (Fig. 4) in relation to the roller 6, whereby the stem, in consequence of the continued downward movement of the gripper, arrives between the rollers and is clamped between them, and whereby the rotated roller 6 brings the roller 7 into rotation so that the stem is pulled (fed) downwards with suitable velocity. The stripping, i. e. the tearing out of the stem, which has previously been effected by the gripper, will thus now be transferred to the rollers.

At the movement of the arm 16 back to its initial position, which movement is governed by the cam disk 19, the abutment 46 on the arm 16 engages the abutment 45 on the arm 36 so that the latter is caused to take part in the movement of the arm 16 to the initial position in Fig. 1.

The device is preferably so arranged that the gripper, after the rollers have caught the stem, moves with a velocity greater than the velocity imparted to the stem by the rollers, whereby the stem is pulled out of the gripper and the latter may begin its upward movement to the initial position earlier so that the last-mentioned movement need not follow so rapidly as would otherwise be the case.

The velocity of rotation of the rollers in relation to the downward movement of the gripper may of course also be such that the rollers and the gripper, the rollers having caught the stem, effect the continued stripping process in cooperation.

The driving device of the gripper may also be so arranged that the gripper stops and opens when the rollers have undertaken its task. The path of the gripper is thereby shortened and the gripper may thus return relatively slowly.

The embodiment shown and described is only given by way of example, it being clear that the invention may be applied in many other ways.

Thus the two rollers may be movable against each other or the inner roller 6 may

be arranged on a rotatable arm and the outer roller 7 stationary. The cutter wheel 33 and the roller 7 may also be arranged on the same arm. Each one of the rollers may be driven separately from the driving shaft 11.

The shaft 60 on which the rear guide roller of the upper band path 2 is rotatably journaled is rigidly connected with the shaft of the fore roller of said band path so that the band path may be swung up and down about the shaft 60, as will be seen from Fig. 1.

How the gripper is constructed in detail, how the shanks thereof, gripping the stem, are actuated in order that the gripper should open and close itself at the right moments, and how the device for driving the gripper carrier up and down is arranged has not been particularly described or shown. The said devices should preferably be constructed in accordance with what is shown in the patent application No. 268,685 filed on the 9th of April, 1928.

What I claim as new and desire to secure by Letters Patent of the United States of America is:—

1. In a machine for stripping the stem from a tobacco leaf, the combination of a device for gripping the leaf and moving it into the machine, a gripper adapted to seize the stem of the leaf, means whereby the said device and said gripper are moved in relation to each other to cause the stem to be pulled from the leaf, a roller device for feeding the stem arranged beside the path of movement of the gripper, and means whereby said roller device is kept in an inoperative position when passed by the gripper, at the beginning of the stripping process, but immediately after this has happened assumes an operative position so as to grip the stem and co-operate in or effect the continued stripping of the stem from the leaf.

2. In a machine for stripping the stem from a tobacco leaf, the combination of a device for gripping the leaf and moving it into the machine, a gripper adapted to seize the stem of the leaf, means whereby the said device and said gripper are moved in relation to each other to cause the stem to be pulled from the leaf, a roller device for feeding the stem, said roller device consisting of two feeding rollers which are arranged one on each side of the path of movement of the gripper, and means for separating and bringing together these rollers.

3. In a machine for stripping the stem from a tobacco leaf, the combination of a device for gripping the leaf and moving it into the machine, a gripper adapted to seize the stem of the leaf, means whereby the said device and said gripper are moved in relation to each other to cause the stem to be pulled from the leaf, a roller device for feeding the stem, said roller device consisting of two feeding rollers which are arranged one

on each side of the path of movement of the gripper, means for separating and bringing together these rollers, a driving shaft, a gearing for transmitting the rotation of the shaft to one of said rollers.

4. In a machine for stripping the stem from a tobacco leaf, the combination of a device for gripping the leaf and moving it into the machine, a gripper adapted to seize the stem of the leaf, means whereby the said device and said gripper are moved in relation to each other to cause the stem to be pulled from the leaf, a roller device for feeding the stem, said roller device consisting of two feeding rollers which are arranged one on each side of the path of movement of the gripper, a member carrying one of said rollers and movable in a direction towards and from the other roller and means for reciprocating said carrying member, said means consisting of a cam disk adapted to move the carrying member in one direction and a spring adapted to move it in the opposite direction.

5. In a machine for stripping the stem from a tobacco leaf, the combination of a device for gripping the leaf and moving it into the machine, a gripper adapted to seize the stem of the leaf, means whereby the said device and said gripper are moved in relation to each other to cause the stem to be pulled from the leaf, a roller device for feeding the stem arranged beside the path of movement of the gripper, a device for cleaning or scraping off leaf portions sticking to the stem after it has been removed from the leaf, said cleaning device being arranged in the path of the gripper means for causing said cleaning device to operate after the gripper has passed the same, said roller device being arranged behind the said cleaning device in the direction of the stripping movement of the stem.

6. In a machine for stripping the stem from a tobacco leaf, a device for cleaning or scraping off leaf portions sticking to the stem after it has been removed from the leaf, said cleaning device consisting of two members arranged on each side of the path of the stem, carrying members for said cleaning members, one of said carrying members being movable in a direction toward, and from the path of the stem, a roller device for feeding the stem, said roller device consisting of two feeding rollers which are arranged one on each side of the path of movement of the stem, a member carrying one of said rollers and movable in a direction towards and from the other roller, and means whereby the carrying member of one roller carries the carrying member of one cleaning member along its movement and brings the latter into and out of operative position.

7. In a machine for stripping the stem

from a tobacco leaf, the combination of a device for gripping the leaf and moving it into the machine, a gripper adapted to seize the stem of the leaf, means whereby the said device and said gripper are moved in relation to each other to cause the stem to be pulled from the leaf, a roller device for feeding the stem, said roller device consisting of two feeding rollers which are arranged one on each side of the path of movement of the gripper, means for separating and bringing together these rollers, a device for cleaning or scraping off leaf portions sticking to the stem after it has been removed from the leaf, said cleaning device being arranged in the path of the gripper, and means whereby said cleaning device is kept in an inoperative position when passed by the gripper, but immediately after this has happened assumes an operative position so as to clean the stem.

8. In a machine for stripping the stem from a tobacco leaf, the combination of a device for gripping the leaf and moving it into the machine, a gripper adapted to seize the stem of the leaf, means whereby the said device and said gripper are moved in relation to each other to cause the stem to be pulled from the leaf, a device for cleaning or scraping off leaf portions sticking to the stem after it has been removed from the leaf, said cleaning device consisting of two members arranged one on each side of the path of the stem, carrying members for said cleaning members, one of said carrying members being movable in a direction towards and from the path of the stem, a roller device for feeding the stem, said roller device consisting of two feeding rollers which are arranged one on each side of the path of movement of the stem, a member carrying one of these rollers and movable in a direction towards and from the other roller, and means whereby the carrying member of one roller carries the carrying member of one cleaning member along its movement and brings the latter into and out of operative position.

9. In a machine for stripping the stem from a tobacco leaf, the combination of a device for gripping the leaf and moving it into the machine, a gripper adapted to seize the stem of the leaf, means whereby the said device and said gripper are moved in relation to each other to cause the stem to be pulled from the leaf, a roller device for feeding the stem, arranged beside the path of movement of the gripper, means whereby said device is kept in an inoperative position when passed by the gripper, at the beginning of the stripping process, but immediately after this has happened assumes an operative position so as to grip the stem and cooperate in or effect the continued stripping of the stem from the leaf, and a scraper arranged in proximity to the rolling device and adapt-

ed to prevent the stem from coiling itself up about the rolling device and to keep this latter clean.

In testimony whereof I affix my signature.

CARL GEORG BERTIL ROTHIELIUS.
